Assignor to

The Lowell Manufacturing Company.

Letters Patent No. 1635, dated Aug. 12, 1862,

The schedule referred to in these Letters Patent and making part of the same,

To all whom it may concern,

Be it known that I, Elémir J. Ney, of Lowell in the County of Middlesex, and State of Massachusetts, have originated and designed a new Pattern for Carpets or other fabrics, of which the following is a full, clear and exact description, reference being had to the accompanying drawings making part of this specification.

A, is one half of an eight pointed figure surrounded by eight leaves resting on the ground of key work, 1.

Surrounding the ground, 1, is a scalloped band, 2, which is itself surrounded by the belt, 3.

B, is one half of a group of leaves and flowers, surrounded by a waving band, resting on the ground of key work, 4. The ground 4, is surrounded by the scalloped band, 5, which is surrounded by the belt 6. Fig. C, is one half of a wreath resting on the veined figure 7, parts of which overlap the belts 3. and 6. Fig. D, is one half of a group of leaves and flowers resting on the veined figure 8. Figs. 9 and 10, are large veined leaves. Figs. 11 and 12, are groups consisting of a flower resting on three large leaves. E, in the centre is a small flower, between which and the belts 3. and 6. are grounds of small crosses. The remainder of the design consists of vines or branches running in various directions.

The colors employed for the different portions of the design may be varied to suit the taste and wish of the manufacturer.

Claim.

What I claim as my invention and desire to secure by Letters Patent, is the design or pattern for carpets or other fabrics, herein set forth.
